CLAIM

The ornamental design for a dove ring, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a dove ring showing my new design;

FIG. 2 is a perspective view of the dove ring of FIG. 1;

FIG. 3 is a perspective view of the dove ring of FIG. 1;

FIG. 4 is an elevation view of the dove ring of FIG. 1;

FIG. 5 is an elevation view of the dove ring of FIG. 1;

FIG. 6 is an elevation view of the dove ring of FIG. 1;

FIG. 7 is an elevation view of the dove ring of FIG. 1;

FIG. 8 is an elevation view of the dove ring of FIG. 1;

FIG. 9 is a perspective view of the dove ring of FIG. 1;

FIG. 10 is a perspective view of the dove ring of FIG. 1;

FIG. 11 is a perspective view of the dove ring of FIG. 1;

FIG. 12 is a perspective view of the dove ring of FIG. 1;

FIG. 13 is a perspective view of the dove ring of FIG. 1;

FIG. 14 is a detailed enlargement perspective view of a portion of the dove ring of FIG. 1; and,

FIG. 15 is a detailed enlargement perspective view of a portion of the dove ring of FIG. 1.

The broken lines in FIGS. 14 and 15 depict break lines that form no part of the claimed design.
